P. PALOMBELLA

SHOE SHINING STAND

Filed June 14, 1923

FIG. 1.

FIG. 2.

FIG. 3.

Pasquale Palombella

— INVENTOR.

BY

Frank A. Cutler, ATTORNEY.

UNITED STATES PATENT OFFICE

PASQUALE PALOMBELLA, OF SPRINGFIELD, MASSACHUSETTS.

SHOE-SHINING STAND.

Application filed June 14, 1923. Serial No. 645,268.

To all whom it may concern:

Be it known that I, PASQUALE PALOMBELLA, a citizen of the United States of America, and a resident of Springfield, in 5 the county of Hampden and State of Massachusetts, have invented a new and useful Shoe-Shining Stand, of which the following is a specification.

My invention relates to improvements in 10 stands furnished in shoe-shining establishments for the accommodation of persons having their shoes blacked, dressed, or polished, and consists essentially of a platform and step, a chair mounted on said platform, 15 foot-rests supported above said step, mechanism for raising and lowering said foot-rests, and mechanism for moving the same forwardly and rearwardly, all as hereinafter set forth.

20 One object is to provide means for positioning the foot-rests of the stand at heights most convenient for the patrons.

A further object is to provide means for 25 locating the foot-rests nearer to or farther from the chair, according to the lengths of the legs of the patrons. This is a feature which is especially desirable when some of the patrons are children.

Still another object is to produce equipment of the character described above which 30 is comparatively inexpensive, simple in both construction and operation, convenient, and withal highly practicable and efficient.

Other objects and advantages will appear 35 in the course of the following description.

I attain the objects and secure the advantages of my invention by the means illustrated in the accompanying drawings, in which—

40 Figure 1 is a top plan of the foot-rest supports and the operating mechanisms therefor, with parts in section; Fig. 2, a vertical section taken on lines 7—7, looking in the direction of the associated arrow, in Fig. 1, 45 and, Fig. 3, a vertical section taken on lines 8—8, looking in the direction of the associated arrow, in Fig. 1.

Similar reference characters designate 50 similar parts throughout the several views.

Inasmuch as the platform and step may be and usually are of sufficient length to accommodate more than one chair and one pair of foot rests, only fragmentary portions

of such a platform and step are shown in connection herewith. 55

In Fig. 3 the foot-rest therein appearing is shown by broken lines in its most elevated rearward position.

The platform and step are of ordinary construction, and respectively indicated by 60 the numerals 1 and 2.

The forward part in side elevation of a chair is illustrated in Fig. 3 wherein a front leg is indicated by the numeral 11, and seat by the numeral 10. 65

The chair is located on the platform 1 adjacent the front edge thereof, and two foot-rests 41 are located above the step 2 in position to receive the feet of the person seated in said chair. Each foot-rest 41 is secured 70 to the top of a vertical rod 42 which extends downwardly through a slot 43 in the top of the platform 2 into a tubular holder 44. The slots 43 in the top of the step 2 are at right-angles to the front edge of said step, and there is a slot 43^a in said top that extends 75 in the same direction as do said first-named slots, but is located nearer the front side of the platform 1. Each rod 42 is provided on the backside with a rack 45, and there is a slot 46 in the corresponding side of the holder 44 in which said rod is located to accommodate a gear 47 that intermeshes with said rack. The two gears 47 are secured 80 on a horizontal shaft 48 that is journaled in bearings 49—49 integral with the back sides of the holders 44. Secured to the left-hand terminal of the shaft 48 is a bevel-gear 50.

A crank-shaft 51 is journaled in the front side of the step 2, and a hollow shaft 52 is 85 journaled in a bearing 53 that extends to the left from the left-hand holder 44, and receives therein the inner terminal portion of said crank-shaft. The crank-shaft 51 and the hollow shaft 52 are rotatably connected, but arranged for independent longitudinal movement, by means of longitudinal slots 54 in said hollow shaft, and a pin 55 that extends from said crank-shaft 51 into 90 said slots. Secured to the rear terminal of the shaft 52 is a bevel-gear 56 which intermeshes with the bevel-gear 50. The bevel-gear 56 and a collar 57 secured to the shaft 52, respectively behind and in front of the bearing 53, hold said shaft against endwise 95 movement in said bearing. Secured to the

front end of the crank-shaft 51 is a crank-arm 58, and also secured to said shaft between said crank-arm and the front side of the step 2 is a ratchet-wheel 59. The ratchet-wheel 59 and a collar 60 secured to the crank-shaft, respectively outside and inside of the front of the step 2, hold said shaft against endwise movement. A detent 61 is pivotally connected at 62 with the front of the step 2, 5 in position to engage the ratchet-wheel 59 and prevent said ratchet-wheel from rotating in a reverse direction. The detent 61 is provided with an extension or handle 63 to facilitate the disengagement by hand of said 10 detent from the ratchet-wheel 59. Each holder 44 is bifurcated at the bottom to receive a roll 64 which is mounted on a horizontal spindle 65 that is journaled in the parts each side of the bifurcation, and there 15 is a track 66 which extends inwardly from the front of the step 2 for said roll, the latter being received in a longitudinal groove 67 in the top of said track.

Upon grasping the handle of the crank-arm 58 and rotating the crank-shaft 51 by means of said handle to the left, the gears 47 are rotated, through the medium of the pin 55, shaft 52, bevel-gears 56 and 50, and shaft 48, in the direction to raise or elevate 20 the racks 45 and with said racks the rods 42 and foot-rests 41. Upon swinging the detent 61 out of engagement with the ratchet-wheel 59, while grasping the handle of the crank-arm 58, and permitting the rotary 25 parts and members to revolve in opposite directions, or causing them to revolve in such directions, the foot-rests 41 are lowered. Thus the foot-rests may be easily and quickly 30 located at any desired height, within the range of the elevating mechanism, where 35 they are locked or secured by means of the detent 61 and intervening members. The rods 42 are moved up and down in the holders 44 simultaneously, and the height of one 40 always corresponds with that of the other.

Extending between and secured to the front and back sides beneath the top of the step 2, and passing between the holders 44, 45 are two horizontal guides 68. In the outer side of each guide 68 is a T-slot 69. Extending toward each other from adjacent sides of the holders 44 are two hubs 70, and mounted on the inner terminals of these hubs are two rolls 71. The arrangement and construction of parts are such that the inner terminals of the hubs 70 extend into the narrower portions of the slots 69, and the rolls 71 are in the wider portions of such slots. Upper and under cross-pieces 72 rigidly connect the 50 holders 44. The foot-rest rods 42 are thus supported in and carried by a rigid structure which is somewhat in the nature of an upright carriage, and the same is movably supported by the rolls 64 in the grooved 55 tracks 66 and the rolls 71 in the slotted

guides 68. It follows, therefore, that a limited amount of forward and backward movement is permitted or afforded the foot-rests 41, whereby the same may be located nearer to or farther from the platform 1.

Having its base pivotally connected at 73 with a floor bracket 74 is an upwardly-extending lever 75. The lever 75 projects through the slot 43^a in the step 1, and has a handle 76 above said step. An angular brace 77 has its ends secured to the cross-pieces 72 intermediate of the ends of such pieces, and has its angle or elbow, which is behind the vertical plane of said cross-pieces, pivotally connected at 78 with the lever 75. Upon grasping the handle 76 and swinging the lever 75 rearwardly on its pivot 72, the brace 77 and with it the holders 44 is moved in the same direction, and, upon swinging said lever in the opposite direction, said brace with said holders is moved forwardly. At such times the rolls 64 travel in the grooves 67 and the rolls 71 travel in the slot 69; also the shaft 52 slides on the crank-shaft 51, and the rear end of the slot 54 approaches or moves away from the pin 55. The holders 44 are moved forward and backward by means of the lever 75 regardless of the elevation of the foot-rests 41. Without the slip connection afforded by the slots 54 and the pin 55, or equivalent provision, the holders 44 could not, of course, be moved in the manner explained.

In order to secure the lever 75 and with it the holders 44 after adjustment, I provide the handle 76 with an ordinary latch 79, and mount a perforated sector 80 on the step 2 at the left of the slot 43^a. The latch 79 is pivotally connected at 81 with the handle 76, and has a part that extends to the left over the sector 80 and carries a pin 82 to enter any one of the perforations in said sector. A spring 83 is interposed between the lever handle and the latch handle normally to retain the pin 82 in locking engagement with the sector 80. By forcing the handle of the latch 79 against the resiliency of the spring 83 toward the handle 76, said latch is rocked on its pivot 81 in a manner to withdraw the pin 82 from engagement with the sector 80, and then the lever 75 can be swung either forwardly or rearwardly. After such movement the latch 79 is released and permitted to reengage with its pin 82 with the sector 80.

More or less change in the shape, size, construction, and arrangement of some or all of the parts of this shoe-shining stand may be made without departing from the spirit of my invention or exceeding the scope of what is claimed.

What I claim as my invention, and desire to secure by Letters Patent, is—

1. The combination, in a shoe-shining stand, with supporting means, and approx-

- imately vertical hollow holders arranged to move horizontally on said supporting means, of rods in said holders, foot-rests mounted on said rods, means to raise and lower said rods in said holders, and means to move said holders on said supporting means.
2. The combination, in a shoe-shining stand, with hollow slotted holders, supporting means for said holders, the latter being movable in a horizontal plane on said means, a shaft supported from said holders, gears on said shaft and extending into the slots in said holders, and means to rotate said shaft, of rods slidingly arranged in said holders and provided with racks to intermesh with said gears, and foot-rests mounted on said rods.
3. The combination, in a shoe-shining stand, with hollow slotted holders, supporting means for said holders, the latter being movable in a horizontal plane on said means, a shaft supported from said holders, gears on said shaft and extending into the slots in said holders, and means to rotate said shaft, of rods slidingly arranged in said holders and provided with racks to intermesh with said gears, foot-rests mounted on said rods, a crank-shaft, and driving means between said crank-shaft and said first-named means.
4. The combination, in a shoe-shining stand, with hollow slotted holders, provided with bottom rolls, track supports for said rolls, a shaft supported from said holders, gears on said shaft and extending into the slots in said holders, and means to rotate said shaft, of rods slidingly arranged in said holders and provided with racks to intermesh with said gears, foot-rests mounted on said rods, a crank-shaft, and driving means between said crank-shaft and said first-named means.
5. In a shoe-shining stand, a pair of foot-rests, approximately vertical movable supporting means for said foot-rests, tracks beneath said supporting means and upon which said supporting means are adapted to move, connecting means between said supporting means, and lateral guiding means for said supporting means.
6. In a shoe-shining stand, a pair of foot-rests, supporting means for said foot-rests, tracks beneath said supporting means, cross-pieces rigidly connecting said supporting means, and guides between which said supporting means are adapted to move, the latter being provided with members to engage said guides.
7. The combination, in a shoe-shining stand, with a pair of foot-rests, approximately vertical movable supporting means for said foot-rests, tracks beneath said means, and guiding means for said supporting means, of a pivotally-mounted lever, and a pivotal connection between said supporting means and said lever, whereby said supporting means with said foot-rests may be moved on said tracks.
8. The combination, in a shoe-shining stand, with a pair of foot-rest, approximately vertical movable supporting means for said foot-rests, tracks beneath said means, cross-pieces rigidly connecting said supporting means, and means above said tracks to guide said supporting means thereon, of a pivotally-mounted lever; and a pivotal connection between said lever and said cross-pieces, whereby said supporting means with said foot-rests may be moved on said tracks.
9. The combination, in a shoe-shining stand, with hollow slotted holders, supporting means for said holders, a shaft supported from said holders, gears mounted on said shaft and extending through the slots in said holders, a crank-shaft journaled at right-angles to said first-named shaft, a shaft supported from one of said holders, also at right-angles to said first-named shaft, means to drive said first-named shaft from said last-named shaft, interengaging means between said crank-shaft and said last-named shaft which permits independent longitudinal movement to said last-named shaft without disconnection rotatively from said crank-shaft, rods slidingly arranged in said holders and provided with racks to intermesh with said gears, and foot-rests mounted on said rods, of a pivotally-mounted lever, and connecting means between said holders and said lever whereby the former may be moved by and with the latter.
10. The combination, in a shoe-shining stand, with hollow slotted holders, supporting means for said holders, a shaft supported from said holders, gears mounted on said shaft and extending through the slots in said holders, a crank-shaft journaled at right-angles to said first-named shaft, a shaft supported from one of said holders also at right-angles to said first-named shaft, means to drive said first-named shaft from said last-named shaft, interengaging means between said crank-shaft and said last-named shaft which permits independent longitudinal movement to said last-named shaft without disconnection rotatively from said crank-shaft, rods slidingly arranged in said holders and provided with racks to intermesh with said gears, and foot-rests mounted on said rods, of a pivotally-mounted lever, connecting means between said holders and said lever whereby the former may be moved by and with the latter, and locking means for said lever.
